UNITED STATES PATENT OFFICE.

THEODORE W. FOSTER, OF PROVIDENCE, RHODE ISLAND.

DESIGN FOR SCISSORS.

SPECIFICATION forming part of Design No. 25,263, dated March 24, 1896.

Application filed February 12, 1896. Serial No. 579,088. Term of patent 7 years.

To all whom it may concern:

Be it known that I, THEODORE W. FOSTER, a citizen of the United States, residing at Providence, in the county of Providence and State of Rhode Island, have invented and produced a new and original Design for Scissors, of which the following is a specification, reference being had to the accompanying drawing, forming a part thereof.

10 The drawing is a view of one side of a pair of scissors.

The leading feature of my design consists in the foliated ornamentation extending from the inner sides of the finger-loops rearward and the beaded outer edges of the finger-loops having a margin of open scrollwork.

15 The scissors-plates 11 are shown in the drawing comparatively short and pointed. They may be of any usual form or dimension.

20 The finger-loop levers 2 have the inner adjacent sides of the finger-loops 3 formed into the rounded stem 4, which branches out rearward into the branches 5 and 6, connected

with the leaves 7. From the branch 5 the row of beads 8 extend along the outer margin 25 of the finger-loop 3 and terminate in the foliated scrolls 9. The scallops 10 10 form the outer margin. The spaces 11 between the scallops 10 and the beads 8 are perforations and give to the scalloped edges a lace-like 30 effect. Between the finger-loops 3 and the scissors-plates the levers are ornamented by the foliation 12 springing from the stem 4 and the foliated scroll 13 which incloses the convex panel 14, the scroll 13 terminating in foliation extending to the beaded ends of the finger-loop levers.

What I claim is—

The design for scissors herein shown and described. 40

In witness whereof I have hereunto set my hand.

THEODORE W. FOSTER.
